UNITED STATES PATENT OFFICE

2,550,630

DEVICE FOR USE IN POLISHING ARTICLES

Robert Whithead, Wolverhampton, England, assignor to The Wolverhampton Die-Casting Company Limited, Wolverhampton, England, and Wilmet-Breder Limited, Birmingham, England

Application March 28, 1947, Serial No. 737,889
In Great Britain April 15, 1946

9 Claims. (Cl. 51—13)

1

The invention relates to polishing articles, and has for its object to provide improved means for such purpose.

Heretofore the polishing of small articles has usually been effected by holding such articles against a fabric bob or mop rotated at a high speed and supplied with abrasive polishing compound.

Means according to this invention comprise a cylindrical container or drum provided on its inner periphery with means for attaching thereto articles required to be polished. Within the drum are placed pellets of material such as felt, rubber, wood or leather, together with an abrasive compound; and centrally mounted in the drum is a rotor having radial projections or beaters.

The articles are secured in relation to the inner surface of the drum with the surfaces more particularly required to be polished directed inwardly. The drum is then closed and may be stationary or caused to rotate. The rotor is rotated, but at a higher speed; and this causes the projections on the rotor to receive the pellets and throw them, together with the abrasive compound, forcefully against the exposed surfaces of the articles whereby the polishing is effected. The pellets, after striking the articles, are carried round by the drum, if the drum is rotated, as is preferred.

An embodiment of the invention is described with reference to the accompanying drawings, in which:

Figure 1 is a side elevation of the device.

Figure 2 is a plan view partly in section of the device shown in Figure 1.

Figure 3 is a vertical longitudinal section of the drum and the parts within showing the bearing and a bevel wheel which drives the drum, and showing also the pulley driving the rotor, but omitting the rest of the device.

Figure 4 is an end view of the drum with its cover omitted.

Figure 5 is a fragmentary sectional view, to an enlarged scale, to illustrate one of the carriers for the goods to be polished.

In these drawings, 9 indicates a rotatable drum comprising an outer casing 10 closed at its inner end by a wall 11 but open at its other end. 12 is an inner casing which is a fit within the outer casing. It is closed at its outer end by a wall 13, but is open at its inner end. The wall 13 is extended radially to form a flange 14 to cover the outer end of the outer casing 10. The flange has on its periphery slotted lugs 15 which are engaged by swivel bolts 16 pivoted on the periphery of the drum 10.

Secured to the outside of the wall 11 is a bevel wheel 17 integrally mounted on a sleeve 18 journalled in a bearing 19 having integral with it two transverse sockets 20, 20a, embracing the inner

2

ends of two aligned shafts 30 and 30a respectively journalled in bearings 21 of a frame 22. Secured to the outer end of the shaft 30a is a quadrant plate 22a which carries an electric motor 23. The quadrant plate has worm teeth 24 engaged by a worm 25 on a shaft 26 journalled in a bearing 27 secured to the frame 22. The shaft 26 is fitted with a hand wheel 28.

By turning the hand wheel 28 the quadrant plate is rocked together with the motor 23 and drum 9.

The bevel wheel 17 engages with a bevel wheel 29 keyed on the shaft 30 fitted with a fixed pulley 31 by which it is driven at a relatively slow speed. 15 32 is the usual loose pulley.

The motor 23 has a pulley 33 which, by a belt 34, drives a pulley 35 on a shaft 36 which passes axially through the sleeve 18 and passes into the casing 10, where it carries a rotor 37 comprising a spider 38, to which is secured a drum 39. Secured to the outer surface of the drum are longitudinal beaters 40. The rotor 37 is driven at a relatively high speed by the motor 23.

The goods to be polished, shown in the drawings as motor car door handles 41, are fitted on to brackets 42 secured to carriers 43 formed as shallow channels with end walls 44, see especially Figure 5. The one end wall of each tray has formed in it a hole to receive a tapered spring-pressed dowel 45 mounted in a ring 46 secured to the inner surface of the casing 12 near its open inner end. The other end wall of each tray has a hole to receive a dowel 47 secured to the inner surface of the wall 13 of the casing 12.

35 To charge the drum 9, the bolts 16 are cast off allowing the casing 12 to be drawn out from the casing 10. The spring-pressed dowels can then be drawn back releasing the carriers 43 and thus allowing ready attachment, to the brackets 42, of the goods to be polished. The brackets will, of course, be formed to suit the particular goods to be polished. The carriers are replaced in the casing and the latter is charged with pellets of felt or other material together with an abrasive compound. The casing 12 is then replaced in the casing 10 and secured by the swivel bolts 16 being engaged with the lugs 15.

The drum 9 and the rotor 37 are then rotated in the same direction or in opposite directions. 50 The turning of the drum causes the pellets and abrasive material to fall on to the rotor 37 from which it is flung, at a high speed, against the goods.

The polishing action is greatly assisted by 55 rocking the drum by the agency of the hand wheel 28.

Having fully described my invention what I claim and desire to secure by Letters Patent is:

1. A device, for polishing articles, and comprising a hollow cylindrical drum, a mass of

pellets and abrasive material in said drum means for supporting said articles on said drum adjacent the inner periphery thereof, closing walls at the two ends on said drum at least one of said walls mounting said supporting means, a rotor axially mounted in said drum, radially disposed projections of said rotor and means for driving said rotor at a relatively high speed, whereby said pellets and abrasive material is forcefully projected against said articles by the action of said rotating projections.

2. A device, for polishing articles, and comprising a hollow cylindrical drum, means for attaching said articles to said drum adjacent the inner periphery thereof, closing walls at the two ends of said drum, means securing said attaching means to one of said end walls a rotor axially mounted in said drum, radially disposed projections on said rotor and means for driving said rotor at a relatively high speed whereby said projections throw pellets and abrasive material forcefully against said articles, and means for driving said drum at a relatively low speed.

3. A device, for polishing articles, and comprising a hollow cylindrical drum, said drum constituted by an outer casing, an inner end wall of said outer casing, an inner casing fitting within said outer casing, an outer end wall of said inner casing, means for securing said inner casing within said outer casing, means for attaching said articles to the inner periphery of said inner casing, a rotor axially mounted in said drum, radially disposed projections of said rotor and means for driving said rotor at a relatively high speed whereby said projections throw pellets and abrasive material forcefully against said articles.

4. A device, for polishing articles, and comprising a hollow cylindrical drum, means for attaching said articles to the inner periphery of said drum, closing walls at the two ends of said drum, a rotor axially mounted in said drum, radially disposed projections of said rotor and means for driving said rotor at a relatively high speed whereby said projections throw pellets and abrasive material forcefully against said articles, and means for rocking said drum.

5. A device for polishing articles, and comprising a hollow cylindrical drum, said drum constituted by an outer casing, an inner end wall of said outer casing, an inner casing fitting within said outer casing, an outer end wall of said inner casing, means for securing said inner casing within said outer casing, means for attaching said articles to the inner periphery of said inner casing, a rotor axially mounted in said drum, radially disposed projections on said rotor and means for driving said rotor at a relatively high speed whereby said projections throw pellets and abrasive material forcefully against said articles, said outer end wall of said inner casing being extended radially to form a flange to cover the outer end of the said outer casing.

6. A device, for polishing articles, and comprising a hollow cylindrical drum, said drum constituted by an outer casing, an inner end wall of said outer casing, an inner casing fitting within said outer casing, an outer end wall of said inner casing, means for securing said inner casing within said outer casing, means for attaching said articles to the inner periphery of said inner casing, a rotor axially mounted in said

drum, radially disposed projections of said rotor and means for driving said rotor at a relatively high speed whereby said projections throw pellets and abrasive material forcefully against said articles, said outer end wall of said inner casing being extended radially to form a flange to cover the outer end of the said outer casing, slotted radially extending lugs of said flange and swivel bolts pivotally secured on the periphery of said outer casing adapted to engage with said lugs.

7. A device, for polishing articles, and comprising a hollow cylindrical drum, means for supporting said articles on said drum adjacent the inner periphery thereof, closing walls at the two ends of said drum, one of which mounts the end of the drum and is removable from the drum with said supporting means a rotor axially mounted in said drum, radially disposed projections of said rotor, a shaft of said rotor passing out through the inner end of said drum, an electric motor for driving said shaft at a relatively high speed whereby said projections throw pellets and abrasive material forcefully against said articles.

8. A device, for polishing articles, and comprising a hollow cylindrical drum, means for attaching said articles to the inner periphery of said drum, closing walls at the two ends of said drum, a rotor axially mounted in said drum, radially disposed projections of said rotor and means for driving said rotor at a relatively high speed whereby said projections throw pellets and abrasive material forcefully against said articles, a fixed frame of the device, a bearing supporting said drum, a transverse support pivotally mounted in said frame and carrying said bearing, a quadrant plate secured to said support, teeth of said quadrant plate, a rotatable member engaging said teeth, a shaft carrying a worm engaging said teeth and being turnably mounted in a bearing of said frame and means for turning said shaft to rock said quadrant and hence to rock said drum.

9. A device for polishing articles comprising a hollow cylindrical drum having inner and outer end walls, means for supporting articles adjacent the inner peripheries of the drum, a rotor axially mounted in said drum, driving means for said rotor including a first bevel wheel secured centrally on the outer surface of one of said walls, a second bevel wheel engaging said first bevel wheel, a transverse shaft driving said second bevel wheel, and means for driving said shaft.
